UNITED STATES PATENT OFFICE.

DELBERT T. HULSE, OF KANSAS CITY, MISSOURI.

DRIER AND DEODORIZER.

Application filed June 13, 1925. Serial No. 37,001.

This invention relates to driers and deodorizers, and it is primarily intended for drying clothes and the like. It is especially adapted to dyeing plants and cleaning plants, although I do not wish to be limited to any especial adaptation of the invention.

The invention particularly relates to the class of driers and deodorizers of the cabinet type comprising an inclosing casing in which the articles to be treated may be suspended from a rotatable carrier in a manner to permit air to be passed through the fabric to evaporate the moisture and carry off the odors. The air is preferably dry and in order to obtain the best results it should be admitted at a relatively low temperature at such an angle to the carrier that the incoming air will serve as the propelling medium to impart a rotative movement to the carrier, and in this connection it may be well to state here that the inlet conduit has two nozzle-like passageways, either of which may be rendered effective while the other is ineffective, so that the air may be admitted to the casing to impinge against the fabric on the carrier on either side of the center of the carrier. Therefore the carrier may be rotated in either of two directions.

Means is also provided for varying the effective port areas of the nozzle-like passageways to vary the velocity of the air as it enters the casing. Means is also provided for cutting off the main conduit from the source of supply when the air impeller ceases to function, so that danger of odors escaping from the casing toward the source of supply will be avoided.

There are other more or less important features incorporated in my invention. These will be specifically referred to herein-after, reference being had to the accompanying drawings, in which—

Fig. 1 is a perspective view of the upper part of the drier constructed in accordance with my invention.

Fig. 2 is a transverse sectional view through the supply conduit, the inlet branches, and through the main part of the casing, certain other parts being shown in elevation.

Fig. 3 is a vertical longitudinal sectional view through the drier.

Fig. 4 is an enlarged perspective view of the hand wheels for controlling the valves

for the nozzles and the deflector valve, and Fig. 5 is a perspective view of the impeller supporting ring.

The cabinet in which the articles to be treated are received is shown as comprising a casing 1, preferably cylindrical and consisting of two spaced walls 1 and 2 provided with a door 3 so that access may be had into the casing. The space 4 between the walls 1 and 2 is preferably filled with strips of insulating material, for example, fibre. By reference to Fig. 3 it will be observed that the ends of the wall members are connected by top and bottom members 5 and 6. Within the casing is a rotatable spindle 7 supporting a carriage 8 which constitutes a support for the articles to be treated. The articles are preferably hung from the periphery of the carriage. The casing is provided with two inlets 9 and 10 separated by a V-shaped wall 11, and they communicate with nozzles or passageways 12 and 13, in turn communicating with an air supply conduit 14. The air supply conduit may receive dry air from any suitable source, the velocity of the air being stepped up by an impeller shown as a motor driven fan 15 fastened to the ring 16 carried by the partition 17 in the conduit 14. The conduit 14 is provided with an opening 18 normally closed by a shutter 19 which is adapted to be swung aside for the purpose of permitting an oiler to be introduced into the conduit 14 to oil the fan motor. The shutter 19 also serves as a damper to vary the effective port area of the opening 18 so that if necessary the air supply opening 20 in the reduced end 21 of the conduit 14 may be augmented. The openings 20 do not supply all of the air for the drier, but in order to increase the absorptive capacity of the air it is sometimes necessary to heat it, so if the air is entering the conduit 14 at too high a temperature, atmospheric air will be let into the conduit 14 to reduce the temperature of the air supply from the normal source of supply.

The air impeller structure is supported on the ring 16 (by reference to Fig. 5) which it will be observed is provided with a sound-deadening filler or ring 22. This may consist of felt or any other suitable material.

In front of the impeller is a damper 23 mounted on a transverse shaft 24 having a crank arm 25 with a counterbalance weight

26 thereon. The counterbalance weight will normally swing the damper 23 across the opening in the partition 17. Therefore back pressure in the casing will be ineffective as soon as it reaches the damper 23, and obnoxious odors cannot permeate the atmosphere of the room in which the casing is located because these odors cannot pass out through the openings 20 nor through the source of air supply, since they will be stopped by the damper 23. However, when the air impeller is operating the force of the air blast against the damper 23 will be sufficient to overcome the counterbalance weight 26, so that air can be forced into the casing. It will be seen that whenever the air impeller stops operating the damper will be effective to close off communication between the source of air supply or the atmosphere, and the casing.

As an important improvement my invention contemplates the provision of means for directing air to either side of the center of the casing and of the spindle 7. This is accomplished by swinging the deflecting valve 27 about its pivot at the apex of the member 11 so that when it strikes against a cleat 28 it will close off port or nozzle 12, and when it strikes against a cleat 29 it will close off conduit or nozzle 13. The pivot for the valve 27 consists of a stem 30 having a hand wheel 31 on the outside conduit 14 so that the valve can be swung back and forth.

It is desirable to change the effective port areas of the nozzles or branch conduits 12 and 13, so I have provided swinging gates or valves 32 and 33 pivoted in the walls of the member 11. The members 32 and 33 have stems 34 and 35 with hand wheels 36 and 37 on their ends outside the conduit, so that they can be turned. The angle at which the members 32 and 33 are swung across the conduits 12 and 13 will determine the effective port area of the particular nozzle involved, it being obvious that the more the nozzle is restricted the greater the velocity of the air, and vice versa. The stems 34 and 35 outside the conduit are provided with ratchets 38 and 39 adapted to be engaged by pawls 40 and 41, and each stem carries a pointer 42 movable over a scale 43. The pointer will indicate the position of the valve in the nozzle conduit, and the dog or pawl will hold the stem against rotation in one direction.

Of course some means must be provided for exhausting the air, so I have provided an exhaust port 44 on the bottom of the casing which may lead to atmosphere.

On the bottom member 6 is a bearing base member 45 in the form of a ring, that is, it is provided with a circular flange 46 which carries a plurality of radially disposed screws 47 adapted to press against and im-

pinge upon an adjustable bearing block 48 having a cup-shaped bearing member or recess 49 to receive the point 50 at the end of the adjustable extension 51 of the spindle 7. The extension is provided with threads which carry jam nuts 52 against the top of which the main body of the spindle 7 rests. The upper end of the spindle 20 has a point 53 engaging a bearing recess or cup 54 carried by the top 5. The extension may be adjustable vertically by loosening the set screws 55 and 56 so that the points properly bear against the recess portions of their bearings or against the walls of the cups.

The spindle can be adjusted to a true perpendicular position by adjusting the screws 47 so as to insure that the adjustable cup member 48 will be in accurate alignment with its complementary bearing member 53. The means for locating the spindle in the casing is elaborated in my application #755,861, so a more extended description of the same in this application is considered unnecessary.

From the foregoing it will be apparent that the carriage may be rotated in two directions so that air can act on the front and back of the fabric, that is, on two sides of the fabric, the alternating operation resulting in a more efficient drying and deodorizing than can be accomplished with a single passage way to the casing.

The means of introducing air into the casing, its control means, and the efficient way in which I eliminate liability of odors passing back through the nozzles to atmosphere, all tend to enhance the value of a device of this kind.

What I claim and desire to secure by Letters-Patent is:

1. In a drier and deodorizer, a casing having two air inlets for directing air into the casing on opposite sides of the axial center of the casing, a rotatable clothes carrier in the casing, means for feeding air to the inlets, and means for alternately directing the air through the inlets so that the air will impinge against the clothes to cause the clothes carrier to rotate.

2. In a drier and deodorizer, a casing having two nozzle-like inlets for directing air on opposite sides of the axial center of the casing, a rotatable clothes carrier in the casing, means for feeding air to the nozzle-like inlets, means for directing air into first one inlet and then the other, and means for varying the effective port areas of the nozzle-like inlets.

3. In a drier and deodorizer, a casing having two inlets and an outlet, the two inlets discharging air into the casing on opposite sides of the axial center of the casing, a clothes carrier concentric within the casing rotatable about its axis, means for delivering air to the inlets so that the air will impinge

against the clothes to rotate the carrier, and means for alternately directing air into first one inlet and then the other.

4. In a drier and deodorizer, a casing having two air inlets and an air outlet, the inlets being located to direct air into the casing on opposite sides of its axial center, a clothes carrier rotatable about the axial center of the casing, independent valve means for the inlets, and means for delivering air to the inlets.

5. In a drier and deodorizer, a casing having air inlet means and air outlet means, a clothes carrier in the casing, an air impeller for delivering air through the air inlet means to the casing, a horizontally pivoted counterbalance baffle between the air impeller and the casing.

6. In a drier and deodorizer, a casing having air inlet means and air outlet means, a clothes carrier in the casing, an air impeller in the inlet means for delivering air under pressure to the casing, and a yielding normally upstanding baffle in the inlet means between the impeller and the casing, the baffle yielding under the pressure of air generated by the impeller.

7. In a drier and deodorizer, a casing having an air inlet means and an air outlet means, an air impeller in the inlet means, 30 the inlet means comprising two nozzle-like tubes discharging into the casing on opposite sides of its axial center, valving means in the tubes, a deflector for directing the air from the impeller into either of the tubes, a yielding baffle between the impeller and the tubes, and a clothes carrier in the casing.

8. In a drier and deodorizer, a casing having an air inlet means and an air outlet means, an air impeller in the inlet means, 40 the inlet means comprising two nozzle-like tubes discharging into the casing on opposite sides of its axial center, valving means in the tubes, a deflector for directing the air from the impeller into either of the tubes, 45 a yielding baffle between the impeller and the tubes, and a clothes carrier in the casing rotatable about the axial center of the casing, so that air delivered into the casing from the tubes will impinge upon the clothes 50 to rotate the carrier.

In testimony whereof I affix my signature.

DELBERT T. HULSE.
